UNITED STATES PATENT OFFICE.

WILLIAM W. SMITH, OF TRENTON, NEW JERSEY, ASSIGNOR TO SANITARY STOVE TOP COMPANY, A CORPORATION OF NEW JERSEY.

GAS-STOVE TOP.

1,171,269.

Specification of Letters Patent.

Patented Feb. 8, 1916.

Application filed July 24, 1915. Serial No. 41,780.

To all whom it may concern:

Be it known that I, WILLIAM W. SMITH, a citizen of the United States, residing at Trenton, in the county of Mercer and State 5 of New Jersey, have invented certain new and useful Improvements in Gas-Stove Tops; and I do hereby declare the following to be a full, clear, and exact description of the invention, such as will enable others 10 skilled in the art to which it appertains to make and use the same.

This invention relates to stove tops, and more especially to the elevating supports intended for use on the tops of stoves which 15 employ fluid or gaseous fuel, and the same embodies improvements over the construction described in my U. S. Patent No. 1,148,412, dated July 27, 1915.

The features of improvement are elaborated in the following specification, shown 20 in the drawings, and specifically covered in the appended claims.

In said drawings: Figure 1 is a plan view showing the application of this attachment 25 to the top of an ordinary gas stove. Fig. 2 is an inverted perspective view of a special form of main section with one side section in place, and Fig. 3 is a sectional view of this main section and two side sections, showing 30 its application to the top of a stove. Fig. 4 is a perspective view of another special form of main section, showing its application to a certain make of gas stove. Fig. 5 is a perspective detail of one end of one of the side 35 sections showing a right-angular tongue, and Fig. 6 a perspective detail of a filler section broken away at the center, this view showing a T-shaped angular tongue. Fig. 7 is a perspective detail of a special form 40 of side section, Fig. 8 shows its application to one side of a main section, and Fig. 9 is a sectional detail on the line 9—9 of Fig. 8.

Most gas stoves now in use have a grated top G surrounded by a solid frame F, and 45 at certain points beneath the grate, usually between the removable sections or spiders therein, are located burners B which are fed with fluid fuel through a main pipe P, valves V and mixers M. The prevailing 50 custom is to employ burners with the neces-

sary adjuncts in rows of two or more, commonly of two, one near the front of the stove and the other farther back. Forward and backward of the stove the spacing of the burners in the many types of gas stoves is 55 nearly the same; but laterally the spacing differs with different manufacturers. Again, some makes of gas stoves have rather wide frames F, some add shelves or ovens at the sides, and some widen the frames at the 60 rear where they are perhaps provided with upstanding flues U to carry off the products of combustion. Therefore provision is made in my former patent for widening this attachment to correspond with the width of 65 the top of the stove, and for reducing the length of this attachment to correspond with the depth of the top of the stove. But I find in certain makes of gas stoves that the two rows of burners are so close together that 70 the standard main sections useful on most gas stoves cannot be employed, and a special form of main section is necessary having four lid openings and otherwise adapted in detail to this make of gas stoves, and this 75 feature of my present invention is shown in Figs. 2 and 3. I also find other forms of stoves on the market, best shown in Fig. 4, in which the gas stove S is formed at the side of a coal stove C, but usually there are 80 three burners disposed in a single row and there are large air inlets A at the front of the structure in addition to the space around the mixers M as shown. This type of gas stove requires another special section whose 85 use is illustrated in Fig. 4. In all cases, however, I find it desirable to close the sides and front ends of the attachment against the escape of heat or the entrance of cold air, and to leave the rear end of the attachment 90 open for the escape of the products of combustion. This is brought about in the present case by special forms of side sections best illustrated in Figs. 5 and 7. I find by experience that it is not always necessary to 95 fasten this attachment to the top of the stove, and that when I do so it is not desirable to bore holes in the top as in my patent; and in the present case I bolt the attachment to the grate as indicated at the left of Fig. 100

1. Whether the attachment is or is not fastened to the stove, I find it desirable to connect the various sections by means which will prevent their disconnection or their relative movement so long as their top plates lie in a single plane; and L-shaped tongues for this purpose are shown in Fig. 5, and T-shaped tongues in Fig. 6.

Referring by numerals to the drawings, 10 the attachment as applied to the ordinary form of gas stove is made up of two main sections 1, 1, an interposed filler section 21, and two side sections 31, 31. The main and filler sections have transverse slats 5 across 15 their rear ends, with break-lines so that they may be removed to adapt the length of these sections to the depth of the top of the stove and to cause the attachment to surround a flue U when it exists. The main sections in 20 this, as in all forms of the present invention, have lid openings 3 wholly or partly surrounded by depending flanges and closed by the pots or by removable lids 4. In main sections of standard make, the two lid openings 25 in each section may be spaced so as to be substantially coincident with the spacing of the two burners forward and backward of the stove, and filler sections 21 of a variety of widths are provided, the workman selecting and employing that one which 30 spaces the openings in the two sections to correspond with the transverse spacing of the rows of burners. So also side sections 31 of proper width are selectively employed 35 to fill out this attachment at its edges and adapt it to the width of the frame F. The filler section is supported at its front end by a flange 24 and at its rear end by legs 29. Each main section is supported at its 40 corners by legs 11 which rest directly on the frame F, and along one or both sides it has depending flanges 10 cut out at 12 between the legs so as to pass over the grate G as seen in Fig. 3, and notched at standard intervals as at 13. With these notches are 45 engaged tongues projecting from the contiguous edges of the supplemental sections for holding all sections connected as long as they remain in a single plane, and finally 50 it is possible to bolt the attachment to the top of a gas stove. All of the features thus far described are set forth in my patent, and no claim is made thereto herein.

The front flanges 24 and 34 of the supplemental sections are as wide as the length of the legs 11, as also is the side flange 30 of each side section 31. The front flange 8 of each main section may also be made of the same width, although in Fig. 2 I have shown 55 it filed off or cut out a little at 9 along its lower edge to pass over irregularities in the frame F or screw heads rising above it, and to permit the escape of the moisture of condensation. This view also shows how

the side flange 30 may be filed off or cut 65 out a little along its lower edge at 39, but we may say that the flanges 8 and 30 come down practically into contact with the frame F, as do the flanges 34 and 24 and the legs 11.

The numeral 23 designates a rib which may be cast beneath the filler section for strengthening purposes, but it is not of width enough to impede the flow of heat beneath this section. The special main section shown in Fig. 2 has a rib 17 running its entire length between its two rows of openings 3, but the lower edge of this rib is cut out as at 12 like the side flanges 10 and therefore it does not seriously impede the flow of heat. The rear end of this rib by preference has a special leg 11' to support the center of the section at its rear end. The standard main sections may have notches 13 in both their side flanges 10, as 35 are shown in both side flanges of the special main section 1' of Fig. 2; but I find that it is not always necessary to apply side sections along both edges of the main section, and where such side sections are not to be 40 used the main sections may have full width flanges such as those illustrated at 30 in Fig. 5. This may apply to a standard main section or to a special form of main section, and in Fig. 4 no side section is shown at 45 the rear of the main section 1'', and the flange 30' along the left side will come down practically into contact with the frame F. The result of this improvement is that, with or without the use of side sections, the front 50 end and both sides of the attachment are closed to the escape of heat or the inlet of cold air. Air to supply products of combustion must find its entrance through the openings provided for it in the gas stove, 55 and the products of combustion can escape out the rear end of the attachment or between its slats 5.

In applying this attachment to the tops of gas stoves of a variety of makes, it sometimes occurs that even the narrowest side section as shown in Fig. 5 and as shown applied in Fig. 4 is so wide that its flange 30 would come out almost to the corner of the frame F and a neat fit could not be 60 made. I have therefore devised a special form of side section best seen in Fig. 7. This can be made of sheet metal cut into the shape of a flat strip 36 having integral tongues 35 projecting from one edge at 65 standard intervals, these tongues being angular and of L-shape or T-shape as hereinafter described, and being bent as best seen in Fig. 7. In applying this section to the side flange 10 of a main section, it is 70 laid against such flange with its shanks opposite the notches 13 and then moved upward so that the shanks enter the notches

and the heads of the tongues slip in behind the flange as shown in Figs. 8 and 9. The strip may be of a width a little less than the length of the legs 11, but in any event its 5 lower edge rests on the frame F and its body covers the space beneath the cut-out 12 while of course it closes the notches 13. The result is that this special side section serves to prevent the escape of heat or the admission of cold air, and therefore possesses the 10 advantages already described.

Along the edges of the supplemental sections are tongues for engaging the notches 13, these tongues being on both edges of the 15 filler section as seen in Fig. 6 and on the inner edge of the side section as seen in Fig. 5. I prefer to make said tongues angular, and have employed Fig. 6 to show them as of T-shape as at 25, while I have employed 20 Fig. 5 to show them as of L-shape as at 25'. Obviously any other angular configuration could be given them, and the shape adopted could be used on all the supplemental sections. In the application of this attachment 25 to a stove top, two standard main sections are selected if the stove is of usual make or a special form of main section if the make of the stove necessitates it. With two main sections 1, a filler section 21 will 30 be interposed as shown in Fig. 1, and this section must be of such width as to space the openings 3 to correspond with the rows of burners. One or more side sections 31 are then applied to fill out the width of the 35 attachment and cause its periphery to parallel the edge of the frame F so as to produce a neat job, and here again side sections of proper width must be selected, even if it is necessary to use an extremely thin section 40 as shown in Fig. 7. With special makes of stoves, a special form of main section will be employed, and in this case there is no filler section and there may be one or two side sections as may be required. In any event, 45 however, I close the front and both sides of the attachment with supplemental sections which rest upon the frame F, unless the side flange or flanges of the main sections are sufficiently wide to do so.

50 One important feature of the present invention is that when the parts of this attachment are assembled, they cannot be moved relatively as long as they remain in a plane. This results from the use of angular tongues such as those described, whose shanks engage with the notches 13 in the main section or sections and whose tips are bent aside at right angles behind the flanges 55 10. If thought desirable, a bolt 18 may be 60 passed down between the slats 5 and through the grate G, where it will receive a washer and a nut, and in this way one or both main sections will be connected with the grate and therefore with the stove, while the sup-

plemental sections are connected with the 65 main sections by the means just referred to. I prefer to make the side section of a length coincident with the depth of the shallowest gas stove on the market, and its rear end 70 is closed by a flange 34' as shown in Fig. 1. 75 The other standard sections are longer, and the slats 5 may be broken off to adapt the attachment to the depth of any stove. The special forms of main sections will not need this feature at their rear ends, as they are 80 made especially for certain types of stoves. The manner of fitting and applying this attachment to a stove top and of using it when placed thereon need not be elaborated.

What I claim is:

1. As a new article of manufacture, an attachment for application to a gas stove, the same comprising a main section having a top plate and depending side flanges provided with notches, other sections whereof 85 each has a top plate and means for supporting the same in the plane of said first-named top plate, and tongues projecting from certain edges of said last-named sections with their shanks engaging said 90 notches and their tips bent aside behind said flanges, whereby the sections cannot be separated while their top plates remain in said plane.

2. The combination with a gas stove including a row of burners and a frame-like top and its grate; of an attachment therefor comprising a main section consisting of a top plate with lid-openings, depending side flanges notched at standard intervals, 100 and a wide flange depending from the front end of the top plate to rest on said frame, this section being open at its rear end; means for closing the notches along one side 105 of said section; and a side section along the other side and having a flange resting at its lower edge on the frame, and right-angular tongues at standard intervals detachably engaging said notches.

3. The combination with a gas stove including a row of burners and a frame-like top and its grate; of an attachment therefor comprising a main section consisting of a top plate with lid openings adapted to align with the burners, depending side flanges 110 cut out at their lower edges to overlie the grate and notched at standard intervals, and a wide flange depending from the front end of the top plate to rest on said frame, this section being open at its rear end; means for 115 closing the cut-out along one side of said section, and a side section along the other side of the main section resting at its lower edge on the frame to close the cut-out in the contiguous flange, and right-angular 120 tongues on the side section at standard intervals detachably engaging said notches.

4. The combination with a gas stove in-

- cluding a row of burners and a frame-like top and its grate; of a removable top comprising a main section having a top plate with lid-openings adapted to aline with the 5 burners in said row, side sections selectively employed along the sides of said main section, flanges along the outer edges of the side sections and the front ends of all sections adapted to rest on said frame, the rear 10 ends of said main section being slatted, bolts passing between the slats and through the grate, and means for holding said sections edge to edge while their top plates remain in a single plane.
- 15 5. The combination with a gas stove including a row of burners and a frame-like top and its grate; of an attachment therefor comprising a main section consisting of a top plate with lid openings adapted to 20 aline with the burners, depending side flanges cut out at their lower edges between the corners of the section to overlie the grate and notched at standard intervals, a wide flange depending from the front end 25 of the top plate to rest on said frame, this section being open at its rear end, and means for selectively removing portions of the section at said rear end; means for closing the cut-out along one side of said section; and 30 a side section along the other side of and shorter than said main section and comprising a top plate adapted to aline with that of the main section, angular tongues at its inner edge adapted to engage said notches, and 35 flanges along its outer edge and both ends for resting on said frame.
6. The combination with a gas stove including a frame-like top and its grate; of a removable top comprising a main section, side sections selectively employed along the 40 sides of said main section, flanges along the outer edges of the side sections and the front ends of all sections adapted to rest on said frame, bolts passing through said main section 45 and the grate, and inter-engaging elements along the meeting edges of all sections for holding them connected while their top plates remain in a single plane.
7. The combination with a gas stove including a frame-like top and its grate; of a removable top comprising a main section, side sections selectively employed along the 50 sides of said main section, flanges along the outer edges of the side sections and the front 55 ends of all sections adapted to rest on said frame, bolts passing through said main section and the grate, depending flanges along the sides of the main section cut out to pass over the grate and notched at standard intervals in their lower edges, and right-angular 60 tongues projecting from the supplemental sections at standard intervals with their shanks passing through said notches and their heads engaging the cut-out flanges

for holding all sections connected while 65 their top plates remain in a single plane.

8. As a new article of manufacture, an attachment for application to a gas stove, the same comprising two main sections whereof each has a top plate and depending side 70 flanges provided with notches, filler and side sections whereof each has a top plate and means for supporting the same in the plane of said other top plates, and angular tongues projecting from certain edges of 75 said last-named sections and engaging said notches, whereby the sections cannot be separated while their top plates remain in said plane.

9. The combination with a gas stove including a plurality of rows of burners and a frame-like top and its grate; of a removable top comprising main sections whereof each has a top plate with lid-openings adapted to aline with the burners in one 80 row, filler sections selectively employed for spacing the main sections laterally to such alinement, side sections selectively employed along the sides of said main sections, flanges along the outer edges of the side sections 85 and the front ends of all sections adapted to rest on said frame, the rear ends of said main sections being slatted, bolts passing between the slats and through the grate, and means for holding said sections edge to edge 90 while their top plates remain in a single plane.

10. The combination with a gas stove including a plurality of rows of burners and a frame-like top and its grate; of a removable top comprising main sections whereof each has a top plate with lid-openings adapted to aline with the burners in one 100 row, filler sections selectively employed for spacing the main sections laterally to such alinement, side sections selectively employed along the sides of said main sections, flanges along the outer edges of the side sections 105 and the front ends of all sections adapted to rest on said frame, bolts passing through said main sections and the grate, and inter-engaging elements along the meeting edges 110 of all sections for holding them connected while their top plates remain in a single plane.

11. The combination with a gas stove including a plurality of rows of burners and a frame-like top and its grate; of a removable top comprising main sections whereof each has a top plate with lid-openings 115 adapted to aline with the burners in one row, filler sections selectively employed for spacing the main sections laterally to such alinement, side sections selectively employed along the sides of said main sections, flanges along the outer edges of the side sections 120 and the front ends of all sections adapted to rest on said frame, bolts passing through 125

said main sections and the grate, depending flanges along the sides of the main sections cut out to pass over the grate and notched at standard intervals in their lower edges, 5 and right-angular tongues projecting from the supplemental sections at standard intervals with their shanks passing through said notches and their heads engaging the cut-out flanges for holding all sections con-

nected while their top plates remain in a single plane.

In testimony whereof I affix my signature in presence of two witnesses.

WILLIAM W. SMITH.
